(57) **CLAIM**

The ornamental design for a tremolo, as shown and described.

DESCRIPTION

FIG. 1 is a first perspective view of an ornamental design for a tremolo showing a first embodiment a portion of a slider feature is shown with the slider feature of the tremolo shown in a first position;

FIG. 2 is a second perspective view thereof;

FIG. 3 is a top view thereof;

FIG. 4 is a bottom view thereof;

FIG. 5 is a front view thereof;

FIG. 6 is a rear view thereof;

FIG. 7 is a left side view thereof;

FIG. 8 is a right side view thereof;

FIG. 9 is an enlarged perspective top view thereof;

FIG. 10 is a first perspective view showing a second embodiment of the an ornamental design for a tremolo a portion of a slider feature is shown with the slider feature of the tremolo shown in a second position;

FIG. 11 is a second perspective view thereof;

FIG. 12 is a top view thereof;

FIG. 13 is a bottom view thereof;

FIG. 14 is a front view thereof;

FIG. 15 is a rear view thereof;

FIG. 16 is a left side view thereof;

FIG. 17 is a right side view thereof; and,

FIG. 18 is an enlarged perspective view thereof.

The evenly spaced broken lines represent the portions of the tremolo and the remaining portions of a guitar environment that form no part of the claimed design. The dot-dashed broken lines in FIGS. 9 and 18 indicate enlarged portions of the design and form no part of the claimed design.
